DESIGN FOR A HAT

Samuel Scheuer, New York, N. Y.

Application December 17, 1938, Serial No. 81,841

Term of patent 3½ years

To all whom it may concern:

Be it known that I, Samuel Scheuer, a citizen of the United States of America, residing in the city of New York, county of New York, and State of New York, have invented a new, original, and ornamental Design for a Hat, of which the following is a specification, reference being had to the accompanying drawing, forming part thereof.

Fig. 1 is a front view of a hat showing my new design.

Fig. 2 is a rear view thereof.

Fig. 3 is a top plan view.

I claim:

The ornamental design for a hat, substantially as shown.

SAMUEL SCHEUER,
